UNITED STATES PATENT OFFICE.

JOSEPH SCHAEFER, OF CLEVELAND, OHIO, ASSIGNOR TO THE VAN DORN IRON WORKS COMPANY, OF CLEVELAND, OHIO, A CORPORATION OF OHIO.

METAL SHELF SUPPORT.

Application filed May 16, 1921. Serial No. 469,904.

To all whom it may concern:

Be it known that I, JOSEPH SCHAEFER, a citizen of the United States, residing at Cleveland, in the county of Cuyahoga and 5 State of Ohio, have invented certain new and useful Improvements in Metal Shelf Supports, of which the following is a specification.

This invention relates to supports for 10 shelves and more particularly to metal shelf supports, such as are used in bookcases or metal cabinets.

The object of the invention is to provide 15 an improved metal shelf support which is of simple construction and can be readily embodied in cases or cabinets where the supporting member is a single metal wall, such as a hollow post; in which the shelf is securely clamped to the supporting members 20 and indeed is more tightly wedged in place by increase in weight thereon; in which the shelf is readily adjusted to various levels by simply detaching a clip and adjusting it to a new position; and finally to provide a construction of this kind embodying a special 25 form of clip or supporting device and a connection therefor to the supporting member.

Other objects of the invention are in part 30 obvious and in part will appear more in detail hereinafter.

In the drawings, Fig. 1 represents a front 35 elevation of a portion of a metal cabinet embodying the invention; Fig. 2 is a sectional plan view on the line 2—2, Fig. 1; Fig. 3 is a perspective view illustrating one of the 40 posts and the clip receiving notches therein; Fig. 4 is a similar view of the adjustable clip; Fig. 5 is a detail sectional elevation on the line 5—5, Fig. 3, showing a portion of a shelf assembled in the cabinet; Fig. 6 is a sectional elevation, similar to Fig. 5, showing a modification; and Fig. 7 is a sectional plan view of another modification.

The invention may be embodied in many 45 forms of cases or cabinets, in fact wherever shelves are to be attached to a support. The drawings show a set of metal shelving embodying corner and intermediate posts 1 connected to each other by the end sheets 2 and 50 a top sheet 3, the lower ends of the posts being suitably connected in any manner, not shown. In the construction of cabinets of this kind the corner posts are frequently made of hollow members, such as the sheet 55 metal channel members shown, and as the

shelves are supported by the flanges of these channels some special supporting device is necessary for connection of the shelf thereto. In the drawings, the inner or shelf supporting flange of each post member is provided with a series of regularly spaced sockets or openings 4 of substantially T form, as shown in Fig. 3, the central portion 5 of each opening extending below the laterally extending wings 6 thereof. These openings are spaced at regular intervals vertically, say an inch apart. By locating them at the same levels on all posts the shelf to be supported is capable of vertical adjustment at intervals of one inch.

For co-operation with each post member there is provided a special clip or shelf securing device shown in detail in Fig. 4. This clip is a metal member having a body portion 7 bent intermediate its ends into channel form, as indicated, to form an extension 8, to enter the recess 4. The extension 8 is also provided with two laterally extending ears or wings 9, one on either side, which are adapted to pass through the wings 6 of the recesses 4. When the clip is moved down with the extension 8 seated in the depending portion 5 of an opening 4 these ears 9 lie behind the re-entrant corners or angle portions 10 of the metal at the opening. Below the projection 8 the body portion of the clip has a depending portion 11 which lies in front of the solid body metal of the post member, as in Fig. 5, and serves to transmit the strain of the weight of the shelf to said member. Above the projection 8, the body portion of the clip is extended upwardly, as at 12, and preferably at a slight angle to the vertical. This upwardly extending portion 12 serves with the wall of the post member to form a recess to receive and confine the shelf or shelf supporting member.

The adjustable clip described may be used in several ways. For example, two of said clips at the same level on adjacent end post members may support a bracket 13 of L form in cross section, as in Fig. 6. This bracket, for example, may be made from a short piece of angle iron. One of the flanges of the angle is pressed down into position between the extension 12 of the clip and the wall of the post member, and to more conveniently enter it into this recess the extreme upper edge of the extension 12 may be bent to a rather sharp incline, as shown

at 14. Upon two angle brackets so supported may be placed any suitable shelf member, such as an ordinary board 15.

In the preferable construction the shelf is 5 of special form embodying within itself the angle bracket. For example, referring to Fig. 5, the shelf there illustrated comprises an angle member of proper length with the horizontal flanges notched out to enable said 10 angle member to be bent around the four edges of the shelf member. Around this bent angle is bent a sheet metal member 16, thereby forming a self contained sheet metal shelf member, with its four edges re-enforced by angles. This shelf is attached to 15 the corner posts by merely pressing the vertical flanges of its sheet metal covered angle members down into the recess between the clip and post members.

With either the shelf shown in Fig. 5, or 20 the angle bracket shown in Fig. 6, the flanges of the angles are slightly tapered or of increasing thickness downwardly. This 25 feature, coupled with the slight inclination of the clip extension 12 serves to wedge the shelf or angle bracket, as the case may be, into the recess of the clip, and therefore not only draw the shelf more tightly toward the post members, but also wedge it solidly into 30 place, the effect increasing with the weight of the shelf and what it supports.

Fig. 7 shows another arrangement where 35 the clips are introduced into T-shaped recesses in a metal plate 20 secured by screws 21 to a wooden wall 22 over a recess 23 therein. The operation is the same as in the other forms before described.

What I claim is:

1. Shelf supporting means, comprising a

vertically extending sheet metal member 40 provided with a series of vertically spaced recesses or openings having enlarged and restricted portions, and a shelf supporting clip formed of sheet metal having a central portion bent into U form, said U-shaped 45 portion being adapted to bodily enter the enlarged portions of said recesses and engage in the restricted portions thereof.

2. Shelf supporting means, comprising a vertically extending sheet metal member 50 provided with a series of vertically spaced T shaped recesses or openings, a shelf supporting clip formed of sheet metal and having a central portion bent into U form to enter said recesses, and provided with lateral wings or ears adapted to lie behind 55 the re-entrant corners of said recesses.

3. In a device of the class described, a shelf supporting clip formed of sheet metal and having a central portion bent into U- 60 form, said U-shaped portion being provided with lateral wings or ears adapted to engage the marginal portions of recesses in a vertically extending supporting member, the end portions of said clip being formed as 65 oppositely extending flanges, one of said flanges being adapted to engage the front marginal portion of an opening in which the clip is inserted to support the weight of the shelf while the other marginal flange 70 is adapted to maintain a spaced relation from the marginal portion of such recess or opening so as to permit the insertion of a shelf for supporting the same.

In testimony whereof I hereby affix my 75 signature.

JOSEPH SCHAEFER.
